UNITED STATES PATENT OFFICE.

BENJAMIN E. GETCHELL, OF PLAINVILLE, CONNECTICUT, ASSIGNOR TO THE TRUMBULL ELECTRIC MANUFACTURING COMPANY, OF PLAINVILLE, CONNECTICUT, A CORPORATION OF CONNECTICUT.

ELECTROMAGNETIC SWITCH.

Original application filed September 22, 1927, Serial No. 221,215. Divided and this application filed December 27, 1927. Serial No. 242,558.

This invention applies particularly to the class of electric switches and similar devices in which an electromagnet and an armature are arranged to cooperate, under certain circuit conditions, to open or close a circuit or to operate co-related parts of the construction.

Devices of this class are usually built up of a comparatively large number of parts 10 mounted on a base being supported by a frame or its equivalent which is in turn secured in an enclosing box.

The magnetically operated armature moves rapidly and stops with considerable impact 15 against the magnet or some part of the construction provided for that purpose. Such constructions usually include a considerable number of screws for holding the parts in position in addition to the usual screws for 20 connecting the circuit wires and the repeated stopping impact of the magnetically operated member against any part of the construction tends to loosen the parts, especially the screws.

25 An important object of my invention is to guard against such danger by providing a construction which will allow for the full and complete movement of the magnetically operated parts in such a manner that the operating impact will not be transmitted to the screws or other co-related parts.

Another object is to provide a simple but compact and reliable construction of the character described.

35 The particular object of my invention is to provide a magnetically operated switch having means for absorbing the operating shock in such a manner that the shock or vibration will not be transmitted to the screws or other 40 parts which ordinarily might become loosened by the repeated operations of the switch.

In the specific form shown herein, the armature is arranged to be moved to effect the desired result although in some cases it may 45 be desirable to provide a movable magnet coil to cooperate with a relatively stationary armature but, in either case, it is my purpose to provide for a certain relative movement between the magnet and its cooperating armature.

In reducing my invention to actual practice, I preferably provide an electromagnet (together with its core and pole pieces as a

unit) with a form of mounting which will permit a limited free movement and a cooperating movable armature which has an operable connection with movable switch contacts or other parts which are to be operated. 55

The magnet unit, the armature, and the switch contacts are so co-related that, when 60 the armature is attracted by the magnet, it will cause a simultaneous movement of the switch contacts and, when the armature strikes against the poles of the magnet unit, the free movement mounting of the latter will 65 permit it to move in response to the impact but, due to this free movement mounting, no shock or impact will be transmitted to the screws or other parts of the construction. In other words, the operating shock of the armature will be absorbed by the magnet unit 70 because of its free movement mounting. After receiving the operating impact of the armature, the magnet will return to its normal position by gravity alone or it may be 75 assisted by suitable spring means.

The contacts and relays are supported on the front of the insulating base and the electromagnetic operator is mounted behind the base. 80

When the armature has completed its movement and rests against the pole pieces of the magnet, it remains in that position against the tension of the spring contacts which will operate to cause a rapid separation of the 85 armature from the magnet when the circuit is broken. These spring contacts also operate to move the magnet unit back into its normal position as it stood before being struck by the moving armature. 90

The foregoing describes the basic ideas of the invention but, in practice, certain refinements of detail are desirable. For instance, it is desirable that some of the shock of the fast moving armature be absorbed by a suitable yielding means before the armature actually strikes against the poles of the magnet and it is also desirable that the switch contacts close with a yielding pressure. These two requirements are provided for by using 95 spring contacts which engage the corresponding stationary contacts before the armature reaches the poles of the magnet and, for the reason that the spring contacts are connected with the armature, the closing impact of the 100 latter is checked. 105

This is a division from my application No. 221,215, filed Sept. 22, 1927.

The accompanying drawings show one form of mechanism embodying improvements 5 of my invention.

Fig. 1 is a front view of the construction but omitting the relay elements.

Fig. 2 is a side view showing one of the 10 relays preferably intended to be used with the construction. Such a relay is shown in my former Patent No. 1,569,364, dated January 12, 1926.

Fig. 3 is a perspective view showing the 15 connecting links between the armature and the movable switch member.

Fig. 4 is a view from the right hand side, the right hand side plate being omitted and parts being shown in section.

Fig. 5 is a vertical sectional view.

20 Fig. 6 is a front view omitting the base and parts being broken away.

Fig. 7 is a view looking upward at the lower end.

Fig. 8 is a rear view, some of the parts 25 being shown in section.

The base or body 15 may be formed of insulating material, such as molded composition. In the form shown the side plates 16 and 17 are of metal and provided with flanges 30 which are secured to the base by screws, such as 18 and 19. The back plate 20 may be secured to the side plates by screws such as 21. This particular form of back plate is adapted for convenient attachment to a back board or 35 in a switch box (not shown). For convenience this back plate 20 is provided with a keyhole slot 22 at the top by means of which it may be conveniently hung on a screw (not shown). The lower corners of this plate 20 40 are provided with notches 23 and 24 which open toward one side and toward the bottom for convenience in mounting the plate under the heads of screws (not shown) in an enclosing box.

45 The line terminals 25, 26 and 27 are mounted on the front face of the base along its lower edge. The load terminals 28, 29 and 30 are mounted in the same plane along the upper edge of the base. The terminals 31, 32 and 50 33 adapted to be connected to a control station or switch are mounted along the upper edge of the base at its rear. The load may be, for instance, a motor (not shown).

The switch has three circuit controlling 55 units in the particular form shown. The left hand unit has stationary contacts 35 and 36 and a movable switch member like 72 (Fig. 5) composed of contact members and connected together by a flexible strip which may be 60 formed of thin laminations so that the two contact members are free to tilt and rock so as to assure perfect contact with the raised portions 40 and 41 of the stationary contacts.

65 The back plate 42 has its ends offset from the plane of its central portion and is provided

with small bosses 44 adapted to rest against the back of the connecting strip 39 so as to permit relative tilting of the contact pieces 37 and 38. The movable contact parts just described and the corresponding movable contacts for the other switch units are all carried by the insulating member 45 which extends across the base of the switch in the form of a cross bar. This cross bar has set in it a flat stud 46, the end of which extends 75 through a spring 49 and a cup-like washer 50. This washer has a central slot 51 to permit it to be slipped on to the end of the stud 46. In this way the movable contact parts 80 may be readily removed and replaced when desired by the simple operation of pressing down upon the washer and turning it with the fingers.

The upper contact 35 of the left hand switch unit is electrically and mechanically secured 85 to the terminal 28 by a screw 54. The lower contact 36 is secured to the clip 55 for the relay 56. The lower clip 57 for the relay is electrically and mechanically connected to the lower terminal 25 by screw 58 which may be 90 seated in a suitable insert in the base in any suitable manner. The intermediate clip 59 for the relay is similarly secured to the base.

The right hand switch unit is constructed 95 in the same manner as the one previously described and has stationary contacts 60 and 61 and a movable contact 62. Relay clips 63, 64 and 65 for the relay 66 are similarly mounted to those previously described. The central switch unit also has stationary contacts 70 and 71 and a movable contact 72. This unit, 100 however, requires no relay and hence the contact 71 is connected directly to the terminal 26 by a strip 73.

The relay 66 (Fig. 2) has end caps 63' and 105 65' to fit the clips 63 and 65 and an intermediate terminal 64' to engage clip 64 of a suitable relay having an automatic thermostatic circuit breaker (not shown) for instance as shown in my former patents.

The carrier bar 45 is provided with insulating flanges 75 and 76 on opposite sides of the central switch unit to serve as barriers between the switch members of the respective units. The base 15 is provided with a transverse groove 77 to receive the cross bar 45 which also serves as a barrier between the contacts of each respective pair of the stationary contacts. The base is also grooved at 78 and 79 to receive the ends of the flanges 115 75 and 76, respectively. The opposite ends of the switch carrier 45 are provided with projecting lugs 80 and 81 which are movably mounted in grooves 82 and 83 in the side plates 17 and 16 respectively.

A cross connecting contact 85 is mounted in the back of the cross bar 45 and adapted to connect the resilient contact members 86 and 87. The two latter contacts are connected respectively to the control switch ter- 120 125 130

minals 32 and 33 and the operation will be explained hereinafter.

At the back of the base 15 is mounted an electromagnet and armature. This magnet 5 has a coil 90 one terminal of which is connected to the control switch terminal 31 and the other terminal of the coil is connected to the intermediate clip 59 for the left hand relay 56. The control switch terminal 33 is 10 connected by wire 91 to the intermediate clip 64 for the right hand relay 66. The core of the magnet which carries the coil 90 in the usual manner is preferably laminated in the customary manner and secured to laterally extending cross bars 92 which are slidably supported in slots 93 in the side plates 16 and 17. The cross bars, magnet, core and coil constitute a vertically movable magnet frame or member. The armature 94 may 15 also be laminated and movable vertically with respect to the magnet coil and core. The armature is connected to the insulating cross bar or contact carrier 45 by a link motion which is supported by the side plates 20 16 and 17.

Lever plates 95 and 96 of substantially bell crank form are pivoted to the side plates 17 and 16 respectively, and connected to the lugs 80 and 81 of the insulating cross bar by 25 links 97 and 98. Extending from these levers 95 and 96 are connecting rods 99 and 100, the lower ends of which are connected to the ends of the cross bar 101 which carries the armature 94. The connecting rods and links 30 99 and 100 may be guided between lugs or projections 102 and 103 formed in the side plates 16 and 17.

When the magnet is energized it lifts the armature 94 and, through the medium of the connecting links 99 and 100, tilts the lever plates 95 and 96, and thus through the pull of the links 97 and 98 draws the contact carrier 45 toward the base so as to cause the movable contacts to engage the stationary contacts. On account of the inclination of the guide slots 82 and 83 the movable contacts slide upwardly on the stationary contacts until fully seated, thus affording a sliding or wiping contact which insures perfect 40 electrical connection. As the contact carrier 45 is drawn backward and upward toward the base, the springs 49 are compressed, thus insuring an even pressure between the contacts and affording a yielding engagement 45 which prevents shock to the parts of the switch. As the cross piece 85 engages the resilient contacts 86 and 87 additional resiliency is provided to bring the parts to rest without shock. In the form shown the electromagnet is vertically movable being guided in the slots 93 so that even the inertia of the moving armature cannot apply a direct blow 50 on the stationary parts of the mechanism.

The magnet circuit may be closed or 60 65 opened in any suitable manner.

In case of overload the magnet circuit will automatically be opened through one or both of the relays. In case of failure of line voltage or abnormal drop of line voltage, the magnet will become weakened and unable to hold the armature against gravity and the force of the springs and the armature will drop away from the magnet thus opening the load and magnet switches. After the switch is once opened, it cannot normally be closed again except by a remote switch or equivalent. This feature is of great value in that it protects the operator against the unexpected starting of the motor or other device after it has once been stopped. 70 75 80

Although I have described the preferred form of the complete apparatus and its method of operation, it should be understood that some of the features may be employed independently of others, for instance, the shock absorbing features herein set forth are applicable to other types of switches, so also it should be understood that the invention is not limited to the use of the particular thermostatic relay herein set forth. It should 85 also be understood that although I have described the invention as particularly applicable to control from a remote point, certain features may be employed without such limitations, for instance, in some cases the control buttons may be mounted directly upon the box which encloses the main switch. I intend that the claims shall be interpreted broadly as they may appear except as may be required by the state of the art or by the 90 95 100 terms thereof.

I claim:

1. In an electric switch, a movable switch member, an electro-magnet and an armature both of which are slidably mounted and vertically movable and one of which is operably connected to said switch member and shock absorbing means for said magnet members. 105

2. An electric switch including a frame, a magnet mounted to slide in the frame, an armature for the magnet mounted to move in the same direction as the magnet with the magnet and independently thereof, stationary and movable contact members one of which is resilient, and means of connection 110 between the armature and the movable contact member. 115

3. An electric switch including a frame having side plates, a magnet having a cross bar guided to slide in the side plates and supported therein, an armature for said magnet, links guided by the side plates and connected to said armature whereby the armature is adapted to move toward and from the magnet and the magnet is adapted to move under impact of the armature, a stationary contact and a movable contact, one of which is resilient, and means of connection between 120 125 130 said links and the movable contact.

4. In an electrically operated switch, both

gravitational means and spring means for absorbing the shock of closure, said gravitational means consisting of a vertically movable magnet having an armature so mounted that the magnet may move upward upon engagement with said armature, and said spring means consisting of yieldable contacts adapted to be moved by said armature.

5. An electrically operated switch mechanism, including a slidably supported magnet, an armature coating with said magnet and mounted so as to move in the same direction as the magnet, a pair of stationary contacts, a contact carrier adapted to be moved by said armature, a pair of movable contacts yieldably supported upon said carrier for engagement with said stationary contacts, said carrier being adapted to approach said stationary contacts at an angle when actuated by said armature so as to produce a sliding engagement between said movable contacts and said stationary contacts and to cushion the operating impact of said armature.

6. In an electrically operated switch, both gravitational means and spring means for absorbing the shock of closure, said gravitational means consisting of a vertically movable magnet having a vertically movable armature, and said spring means consisting of yieldable contacts adapted to be moved by said armature and serving as a resilient abutment for said armature.

7. A switch frame having guide slots, and guide lugs, a magnet frame member guided to slide in said slots, a magnet armature member guided between said lugs and a resilient switch contact operated by the movement of one of said magnet members.

8. A switch frame having guide slots, and guide lugs, a magnet frame member guided to slide in said slots, a magnet armature member guided between said lugs, a switch member actuated by one of said magnet members and a resilient stop for said switch member.

BENJAMIN E. GETCHELL.
